(57) **CLAIM**

The ornamental design for a connectivity module for data link, as shown and described.

DESCRIPTION

FIG. 1 is a perspective view of a connectivity module for data link, showing my new design;

FIG. 2 is a front elevation view thereof, the rear elevation view being a mirror image of that shown;

FIG. 3 is a left side elevation view thereof, the right side elevation view being a mirror image of that shown; and, FIG. 4 is a top plan view thereof, the bottom plan view being a mirror image of that shown.
